UNITED STATES PATENT OFFICE.

ROBERT W. SCOTT, OF PHILADELPHIA, PENNSYLVANIA, ASSIGNOR TO SCOTT & WILLIAMS, INC., OF PHILADELPHIA, PENNSYLVANIA, A CORPORATION OF NEW JERSEY.

CAM MECHANISM FOR KNITTING-MACHINES.

1,221,610.

Specification of Letters Patent. Patented Apr. 3, 1917.

Application filed June 30, 1911. Serial No. 636,278.

To all whom it may concern:

Be it known that I, ROBERT W. SCOTT, a citizen of the United States, and a resident of Philadelphia, in the county of Philadelphia and State of Pennsylvania, have invented an Improvement in Cam Mechanism for Knitting-Machines, of which the following description, in connection with the accompanying drawings, is a specification, like characters on the drawings representing like parts.

This invention relates to cam mechanism for knitting machines, and is applicable to knitting machines both of the straight and of the circular type. I have chosen in this embodiment of my invention to represent it in connection with a circular knitting machine and of that type thereof illustrated in United States Letters Patent to George D. Mayo, No. 726,178, April 21, 1903. Obviously, however, my invention is not limited thereto.

Referring more particularly to the drawings:

Figure 1 is a plan view of a portion of a cam cylinder of a knitting machine provided with my invention;

Fig. 2 is an inside elevation, partially in transverse section, of my invention;

Fig. 3 is a vertical section upon the line 3-3 of Fig. 2;

Fig. 4 is a transverse section through the cam mechanism below the stitch cam;

Fig. 5 is a perspective view of the needle platform or support co-operating with the single stitch cam; and

Figs. 6 and 7 are respectively a vertical section and perspective view of a modified form of my invention.

Referring for convenience of description to that type of knitting machine embodied in the said patent to Mayo, No. 726,178, it is to be observed that therein a single stitch cam is provided. It has been found in practice that when the needles are traveling down the incline of the said stitch cam, they are carried with such force and velocity that they impinge upon the co-operating side cams (depending upon the direction of rotation of the cylinder) where the said side cams meet immediately under the nose of the single stitch cam and indent and wear away the cam at such point. The result is to form an enlargement at this point, and in consequence thereof such of the needles

as move the more freely in the grooves are caused to draw longer stitches than those drawn by the other needles of the set and which do not move so freely. Objectionable lines therefore appear in the finished fabric. 60 In accordance with my invention I provide means for positively limiting the draft of the needles, so that under all conditions the said draft is uniform.

Referring more particularly to the drawings, a portion of the cam cylinder of the machine is represented at 1 in the several figures, the said cylinder being rotated and reciprocated in any suitable manner. Obviously, however, the cam cylinder or carrier 70 may be stationary and the needle cylinder or carrier may be rotated or reciprocated. Suitably mounted upon the cam cylinder, and if desired, in the manner shown in said patent, is a cam bracket 2 having secured thereto by a screw 3 or otherwise a single 75 stitch cam 4 generally similar, it may be, to that shown in said patent and with which co-operate the elevating cams 5, 6. Between the said cams 4, 5 and 6 is the usual cam 80 track 7.

In each direction of rotation of the cam cylinder, there is danger, as previously explained, that the cam 5 or 6 may be worn away by contact of the needles therewith. 85 In order to avoid this, I have provided protecting means embodied in this type of my invention in a platform or support positioned at or adjacent the nose of the stitch cam 4 and serving effectually to cover up 90 the joint 8 between the side cams 5, 6 and also rendering it impossible for a needle to receive more draft than that intended to be imparted thereto by the stitch cam 4.

Beneath the stitch cam bracket 2,—that is, between it and the cam ring 1,—is a space 9 wherein is inserted an angular platform or support 10, the upstanding part 11 whereof may be secured to the cam ring by a screw 12 passing through a vertically elongated 100 slot 13 in said upstanding part, thereby permitting vertical adjustment of said platform or support. Preferably the upstanding part 11 of the support is received in a vertical groove 14 in the outer surface of the said bracket 2, as shown in Fig. 1, thus positioning said support radially inside of adjacent stationary parts of the knitting mechanism. The platform or support 10 may be modified in form, material and otherwise within 110

the scope of my invention. I have, however, shown the foot 15 thereof entering the space 9 as sufficiently long to make perfect engagement with the short needle butts. Preferably the elevating cams 5, 6 are cut away for the greater portion of their thickness as indicated at 16 in Figs. 3 and 4, and preferably laterally beyond the platform or support 10 in both directions, as clearly indicated in Fig. 4, thus leaving a thin part 17, as shown in Fig. 3, the upper edge whereof is preferably flush and makes a tight joint with the inner edge of the foot 15 of the support 10. Owing to the described construction of parts, each needle as it travels down the cam track 7 in either direction will contact with the upper surface of the foot 15 of said support whatever be the length of needle butt and will travel over the upper surface of the said foot 15 until it contacts with the working face of the opposite elevating cam 5 or 6 as the case may be.

It will be observed that the platform or support 10 constituting the present embodiment of means for limiting the draft of the needles, is herein attached to and practically forms part of the bracket 2 carrying the stitch cam 4. Therefore the said support 10 is movable with said bracket, and when wear occurs in the guideways wherein said bracket is mounted, and which may be similar to those shown in said Patent No. 726,178, the said support maintains a fixed relation with respect to the nose of the stitch cam. If, on the contrary, a platform or support were permanently attached to the elevating cams 5 or 6, the space between the said platform and the nose of the stitch cam 40 would constantly increase as wear occurs. Obviously any suitable means may be employed in order radially to move the stitch cam 4. In Fig. 3, I have shown a pin 18 with which cooperates a suitable lever or other device for imparting radial sliding movement to said cam bracket 2 in its guide ways 29.

While the support or platform 10 may be of any suitable material and may in certain cases constitute a yielding or spring like member (in which case it might be made of sufficiently thin steel), I preferably form the said platform or support of rigid or substantially springless material, inasmuch as the pressure of the foot 15, being of spring material, would cause wear of the ends of the stitch cam.

It is, of course, evident that in conjunction with the stitch cam 4 or other suitable cam mechanism I may employ suitable narrowing and widening devices of the form shown in said Mayo patent or of any other suitable type.

In Figs. 6 and 7, I have shown a slightly modified form of my invention, wherein I

avoid the upstanding part 11 of the support, as in certain types of machines there is very little space between the outer edge of the movable cylinder and the stationary parts of the mechanism. In said figures, the support is indicated at 19, it being tapped at 20 for the reception of a screw 21 by which it is secured to the under face of the cam bracket 2, the said support being also tapped at 22 to receive adjusting screws 23, by which the position of the support may be accurately and readily adjusted.

It will be observed that in both forms of my invention here illustrated, there is capacity for vertical adjustment of the platform or support. This constitutes an important feature of my invention.

From the foregoing description, it will be evident that I have provided protecting means which may be of general application, but which peculiarly coöperates with a single stitch forming cam of the type shown in said Mayo patent. The said protecting means insures uniform draft upon all the needles in the knitting operation.

Having thus described one illustrative embodiment of my invention, I desire it to be understood that although specific terms are employed, they are used in a generic and descriptive sense and not for purposes of limitation, the scope of the invention being set forth in the following claims.

Claims:

1. Cam mechanism for knitting machines comprising in combination a movable stitch cam having an attachment fixed thereto and movable therewith, for contact with the needles thrown beyond the active face of the stitch cam, to preserve uniform draft upon the needles.

2. Cam mechanism for knitting machines comprising in combination a movable stitch cam having an attachment fixed to and movable therewith, and means to adjust said attachment relatively to the stitch cam and into a position to contact with the needles thrown beyond the active face of the stitch cam, to preserve uniform draft upon the needles.

3. Cam mechanism for knitting machines comprising in combination a cam cylinder, a cam bracket supported thereon, and radially movable with respect thereto, a stitch cam secured to said bracket, elevating cams on said cylinder coöperating with said stitch cam and a needle support or platform unyieldingly secured to said bracket and underlying the nose of said stitch cam.

4. Cam mechanism for knitting machines comprising in combination a single stitch cam movable into and out of contact with the needles, a pair of elevating cams coöperating therewith, and a needle support or platform held in fixed relation with respect to said stitch cam adjacent the nose thereof,

and overlying portions of said elevating cams when the stitch cam is in its operative position, thereby to receive the impact of needle draft.

5. Cam mechanism for knitting machines comprising in combination a cam cylinder, a radially movable cam bracket mounted thereon, a single stitch cam secured to said bracket, a pair of needle elevating cams having portions of their needle guiding edges removed, and a needle platform or support secured to said bracket and extending to a point underlying the nose of said stitch cam, the inner edge of said platform or support being received by said elevating cams at the point where portions of their guiding edges are removed.
6. Cam mechanism for knitting machines comprising in combination a stitch cam, a coöperating elevating cam having a portion of its needle guiding edge removed and a needle platform adjustably secured in a fixed relation to said stitch cam and inserted between the nose thereof and said elevating cam at a point where a portion of the needle guiding edge of the latter is removed.
7. Cam mechanism for knitting machines comprising in combination a stitch cam for imparting draft to the needles, a needle elevating cam and a platform fixed with relation to said stitch cam for limiting the draft of the needles, the inner edge of said platform extending inward beyond the outer face of the stitch cam.
8. Cam mechanism for knitting machines comprising in combination a stitch cam for imparting draft to the needles, a needle projecting cam having a portion only of the needle guiding edge thereof removed opposite the nose of the stitch cam, and a needle support or platform adjustably secured in a fixed relation with said stitch cam and having the needle receiving surface thereof substantially flush with the unreduced portion of the needle guiding edge of the projecting cam.
9. Cam mechanism for knitting machines comprising in combination, a single stitch cam, a pair of elevating cams coöperating therewith, a needle support or platform held in fixed relation with respect to said stitch cam adjacent the nose thereof and overlying portions of said elevating cams, thereby to receive the impact of needle draft, and means to adjust said support or platform vertically toward and from the nose of the stitch cam.
10. A cam mechanism for knitting machines comprising in combination, a cam cylinder, a stitch cam radially movable with respect thereto; a needle support having predetermined fixed relation to said stitch cam to preserve uniform draft upon the needles, and means to adjust said support vertically toward and from said stitch cam.

In testimony whereof, I have signed my name to this specification, in the presence of two subscribing witnesses.

ROBERT W. SCOTT.
